SHEAR MACHINE

Application filed January 31, 1929. Serial No. 336,498.

The present invention relates to shear machines.

The object of the present invention is to provide a shear machine by which the shear cylinder and blade are automatically removed from contact with the fabric upon the approach of a seam or imperfection in the cloth.

To this end, the invention consists of the shear machine hereinafter described and particularly defined in the claims.

In the accompanying drawings, Fig. 1 is a side elevation of so much of the shear machine as is necessary to arrive at an understanding of the present invention; Fig. 2 is a front elevation of the machine; Fig. 3 is a detail plan view of the feeler; Fig. 4 is a detail view of the switch mechanisms in the open position; Fig. 5 is a view similar to Fig. 4 showing the switches in closed position; and Fig. 6 is a wiring diagram of the electrical connections.

The illustrated embodiment of the invention comprises a shear machine having a frame 8, a shear cylinder 10 provided with the usual helical cutters, and a shear blade 12 which cooperates with the cylinder to cut the nap of the cloth. The cylinder and blade are mounted in supporting arms 14 which are journaled in bearings 16. The cylinder is driven by any usual means (not shown). The cloth 18 passes between brush rolls 22 and 24 and over idler rolls 20 and 26 to the rest 28 which presents the cloth accurately to the cylinder and blade. In order to permit seams or imperfections in the cloth to pass through the machine without being cut by the cylinder, provision is made for raising the cylinder and blade by turning the supporting arms 14 on their pivots 16. To this end, the rear end of each arm 14 is connected by a link 30 with a lever 32 which is pivoted at 34 in the frame. The front ends of the levers 32 are connected at the front of the machine by a foot depressor rod 36.

The machine thus far described is similar to that commonly used for the purpose of shearing textile goods. In operation, the cloth 18 consists in a number of lengths of cloth which are united by seams one of which

is indicated at 38. Inasmuch as the clearance between the blade and the rest is necessarily small, the passage of the seam through the cylinder would result in severance of the cloth. It is therefore necessary that the operator depress the foot rod 36 as the seam approaches the cylinder, thus raising the cylinder out of contact with the cloth and permitting the seam to pass through uncut. According to this usual mode of operation, a considerable burden is placed on the vigilance of the operator. Considerable wastage is caused by the fact that an operator will usually raise the cylinder too early in order to assure free passage of the seam under the blade. Moreover, constant attendance is necessary, and an operator is required for each machine.

According to the present invention, provision is made for automatically lifting the cylinder and blade at a predetermined time in the approach of the seam toward the cylinder. To this end, there is provided a motor 40 connected by a worm 42 and a worm gear 44 with a cam shaft 46 extending across the front of the machine directly above the depressor rod 36. Mounted on the cam shaft is a cam 48 which engages with a cam plate 50 on the depressor. Automatic mechanism is employed for imparting a single revolution to the cam shaft upon approach of a seam toward the cylinder.

This automatic mechanism comprises a detector or feeler indicated generally at 52 mounted directly above the positioning roll 26. The feeler comprises a shaft or rod 54 journaled in opposite sides of the frame and having mounted thereon an angle iron support 56 to which is secured a feeler plate 58 which lies directly in the rear of the cloth, very nearly touching the cloth in the normal operation of the machine, and so arranged that the presence of a seam will turn the feeler rod into the position shown in Fig. 5. As a matter of additional precaution, a pair of feeler loops 60 are mounted at opposite ends of the feeler assembly. Each loop 60 comprises a wire loop attached to a block 62 on the feeler plate. As shown in Fig. 3, the loop comprises two parallel lengths of wire sep-

arated by a distance only slightly greater than the normal thickness of the cloth and so arranged that a seam engaging the rearward length of wire will also rotate the feeler into 5 the position shown in Fig. 5.

Rotation of the feeler into the position of Fig. 5 is utilized to close an electrical switch indicated generally at 63. This switch comprises a contact arm 64 secured to a collar 66 10 on the feeler shaft and carrying an electrical contact 68 which is adapted to engage a contact 70 mounted on an arm 72. The arm 72 is pivoted at 74 on a bracket 76 attached to the frame. A spring 78 normally holds the 15 arm 72 in the position shown in Fig. 4. The switch 63 comprising the contacts 68 and 70 is momentarily closed upon the passage of the seam through the feeler. When the feeler is rotated, as shown in Fig. 5, the switch is 20 closed and the arm 72 is turned slightly on its pivot 74. As shown in Fig. 6, the closing of the feeler switch 63 closes a circuit extending from the supply lines 80 through the 25 solenoid 82 of a magnetic relay switch 84. This switch is a double pole switch of any 30 usual form having movable contact members 86 and 88. Upon closure of the relay switch, a circuit is closed from the line through the pole 86 and the armature 90 of the motor 40 and another circuit is closed through the pole 86, the field winding 92 of the motor, and the speed controlling field rheostat 94. The 35 motor therefore starts turning the shaft 46. Provision is made upon initiation of the rotation of the shaft 46 to close a parallel circuit through the motor in order to maintain the motor in operation for a complete revolution of the cam shaft. This is necessary because of the fact that the feeler switch 63 is 40 only momentarily closed during the passage of the seam through the feeler. Accordingly, a crank rod 96 is pivoted in a collar 98 fixed to the end of the shaft, the crank rod being 45 adjustably connected by a block 100 with a switch actuating rod 102 which controls the operation of the swing contact switch 104. As shown in Figs. 4 and 5, the switch 104 has 50 a fixed contact 106 and a movable contact 108, the latter being normally maintained in a position out of engagement with the fixed contact by an insulating head 110 on the end of the rod 102. A spring 112 normally tends 55 to close the switch. As the cam shaft 46 starts to rotate, the rod 102 is retracted into the position shown in Fig. 5, thereby permitting the switch 104 to close and complete a circuit from the line through the switch 104, the pole 88 of the magnetic switch and the 60 armature and field of the motor. It will be seen that although the engagement of the seam with the feeler is of short duration, the closing of the feeler switch 63 extends over a sufficient period to permit the switch 104 to 65 be closed by operation of the motor. In this connection, it will be seen that the pivoted

arrangement of the feeler switch contact arm 72 is of importance because after closure of the feeler switch as shown in Fig. 5, the switch is held closed during the return of the contacts 68 and 70 to their original position, the 70 length of time required for this return being sufficient to permit the motor to be brought into operation to close the switch 104. At some time after the switch 104 has been closed and before the cam shaft makes a complete revolution, the feeler switch will open, but the motor circuit is then closed through the 75 switch 104.

The motor having been started by the engagement of a seam with the feeler, it will 80 continue to operate for a complete revolution of the cam shaft. The cam 48 depresses the plate 50, thereby lifting the cylinder and blade from the cloth. The speed of the motor is so adjusted that the seam will have 85 barely sufficient time to pass over the rest before completion of a single revolution of the cam. At the end of the revolution of the shaft, the cylinder and blade are returned to normal position and the rod 102 is restored to 90 its original position, thereby lifting the contact arm 108 and opening the switch 104. The switch, being thus opened, de-energizes the solenoid 82 and cuts off the current to the 95 motor, leaving the mechanism in readiness for operation upon passage of another seam toward the cylinder.

A manually operated main switch 114 is included in one side of the line.

In order to indicate the number of times 100 of operation of the lifting mechanism, a counter 116 is operated by the movements of the rod 102. As shown in Figs. 1 and 2, the counter comprises a stationary plate 118 having a single display opening to show a numeral marked on a rotating rear plate 120. The rear plate is mounted on a shaft 122 to 105 which is secured a ratchet 124. A pawl 126 mounted on the rod 102 engages the ratchet and is adapted to advance the ratchet by one tooth upon each rotation of the cam shaft.

It will be seen that the present invention 110 not only eliminates the necessity for constant attendance on the machine, but also possesses the advantage that inasmuch as the cylinder is automatically raised at a predetermined time in the passage of the cloth, the operation may be gauged to cause a minimum wastage of unsheared goods. Moreover, passage of 115 any imperfections, which might be of sufficient thickness to cause cutting of the cloth, and which might not be observed by the operator, will render the mechanism operative to 120 raise the cylinder.

It will be understood, that the term "fabric" 125 is not to be considered as limited to a textile fabric, but includes any material having a surface adapted to be sheared by a shear cylinder and blade.

The invention having been thus described, what is claimed is:

1. A shear machine comprising a shear cylinder and blade, a feeler adapted to be engaged by a seam or imperfection in the material to be sheared, a feeler switch associated with the feeler, a motor, means for starting the motor upon closing of the feeler switch, a cam associated with the motor, connections between the cam and the shear cylinder and blade for lifting the cylinder and blade out of engagement with the material, a crank associated with the motor, a motor switch adapted to be closed upon movement of the crank, a counter associated with the crank, the motor switch being adapted to be opened by the crank upon completion of a single revolution of the cam.
2. A shear machine comprising a shear cylinder and blade, a manually operable device to lift the shear cylinder and blade, a feeler adapted to be engaged by a seam in the material to be sheared, a feeler switch associated with the feeler, a motor independent of the drive for the machine, means for starting the motor upon closing of the feeler switch, a cam driven by the motor, connections between the cam and the manually operable device for lifting the cylinder and blade out of engagement with the material, a crank associated with the motor, and a motor switch adapted to be closed upon initial movement of the crank and to be opened by the crank upon completion of a single revolution of the cam.

In testimony whereof I have signed my name to this specification.

ADOLPH BORN.
